UNITED STATES PATENT OFFICE.

JAMES J. HARTLEY AND JOSEPH M. STRYHAL, OF SCHENECTADY, NEW YORK, ASSIGNORS TO BROWN & SHARPE MANUFACTURING CO., OF PROVIDENCE, RHODE ISLAND.

CENTER-PUNCH.

SPECIFICATION forming part of Letters Patent No. 783,749, dated February 28, 1905.

Application filed April 26, 1904. Serial No. 204,970.

To all whom it may concern:

Be it known that we, JAMES J. HARTLEY and JOSEPH M. STRYHAL, citizens of the United States, residing at Schenectady, in the county 5 of Schenectady and State of New York, have invented a new and useful Improvement in Center-Punches, of which the following is a specification.

This invention relates to improvements in 10 punches, and refers more particularly to a centering and prick punch for machinists' use in making suitable indentations in metal preparatory to drilling the same.

The object of this device is to produce a 15 neat and compact tool for the purpose mentioned in which all of the elements necessary to produce the desired indentation are confined within a suitable handle or case and brought into action automatically by the mere 20 pressure of the prick-point upon the article to be indented.

Another object of the invention is to produce a center-punch operated by a spring-pressure to indent the metal without the use 25 of a hammer or other independent driving device, whereby the indentation forming the center may be accurately located and impressed on the metal without any radial or lateral strain exerted on the punch.

30 Further objects will appear in the subsequent description.

In the drawings, Figure 1 is an elevation of 35 a tool embodying our invention. Figs. 2, 3, and 4 are vertical sectional views through the device seen in Fig. 1, showing the operation and manner of applying the same, the parts being normal in Fig. 2 and partially compressed in Fig. 3 and the striker-plunger as 40 operated in Fig. 4 to produce the desired indentation. Figs. 5, 6, 7, 8, and 9 are detail views of the detached parts of our invention.

Similar reference characters indicate corresponding parts in all the views.

In carrying out the objects stated we provide 45 a suitable case, which not only serves to inclose and guide the movable parts hereinafter described, but also forms a handle by which these parts may be brought into action.

This case is shown as consisting of a slightly-tapering tubular body 1, having a tubular tip 50 or guide 2, secured to the lower part of the concentric tubular body, while the upper part is normally closed by a cap 3, also secured to the main body 1. A punch-rod 4 is reciprocally movable in the lower end of the case and 55 extends above and beneath the opposite ends of the section 2, in which it is guided, the lower extremity being tapered to a sharp point 5, which lies in the axis of the punch-rod and tubular body 1 and serves to produce 60 the desired indentation in a manner hereinafter described. The upper end of this punch-rod 4 is provided with an enlarged head 6, which is guided in a cylindrical chamber 7 in the lower end of the tubular body 1. The 65 upper end of the tubular section 2 is provided with a bushing 8, which encircles the punch-rod 4 and forms an additional guide for the said rod in its reciprocal movement, the bushing being usually screwed into the upper end 70 of the section 2, which latter is drawn in to form a guide for the lower end of the punch-rod. This rod 4 is provided with laterally-projecting shoulders 9, located between the bushing 8 and an annular shoulder 10 at the base 75 of the section 2, and between the shoulders 9 and bushing 8 and encircling the rod 4 is a coil-spring 11, which operates to force the punch-rod 4 downwardly, so that the shoulders 9 normally rest upon the shoulders 10, as 80 seen in Fig. 2.

The head 6 of the punch-rod 4 is provided with a recess 12, Fig. 9, in which is inserted one end of an upright pawl 13, rising from the head 6, the lower end of the pawl, which 85 enters the recess, being reduced in width, so as to form lower and upper shoulders on the pawl which engage the opposite faces of the head 6 to hold the pawl from endwise displacement and at the same time to permit the 90 pawl to be moved positively endwise by the movement of the punch-rod 4, it being understood that although the pawl 13 is removable laterally from engagement with the head when the parts seen in Fig. 9 are detached from the 95 main body 1 said pawl is held in its upright

position from lateral displacement by the adjacent side wall of the central body 1 when the parts are assembled.

A plunger or striker 14 is reciprocally movable in the upper end of the main body 1 and consists of a cylindrical body, of iron or equivalent material, having a lengthwise groove 15 in one of its upright faces for receiving a tripping member 16, said groove being extended 10 upwardly from the lower face of the plunger or striker 14 and is also adapted to receive the upper end of the pawl 13 when it is tripped. This pawl 13 is provided with a tooth 17, which normally engages the lower face of the 15 plunger or striker 14, which is undercut to form an engaging tooth, and the pawl is held in this position by a spring 18, said pawl being adapted to elevate the plunger or striker 14 against the action of a spring 19 when the 20 point 5 is engaged with the article to be indented and when the handle or case is depressed. The spring 19 is arranged within the case and is interposed between the cap 3 and upper end of the plunger or striker 14, 25 so that when the plunger or striker is elevated against the action of the spring in the act of making an indentation in the article the trip 16 automatically releases the tooth 17 of the pawl 13 from engagement with the plunger or striker and the spring 19 instantly operates the plunger or striker downwardly with considerable force against the upper end of the punch-rod 4, thereby producing the desired indentation, which indentation may be 30 deepened by repeating the operations just described, and the tension of the spring 19 may be varied by adjusting the cap 3.

The tripping member 16 is removably secured to the tubular body and is held in place 40 by a stud or pin 20, which enters an aperture 21 in the side wall of the inclosing case, said stud being secured to the tripping member and is simply inserted in the aperture to hold the member from endwise movement, it being 45 held from lateral movement by the plunger or striker and adjacent wall of the case, between which parts the said member is located.

In the operation of our invention the point 5 is first located at the desired point upon the 50 article to be indented, whereupon the device is brought to an upright position and the operator engages the case or handle and depresses the same, first against the action of the spring 11 and then against the action of the spring 55 19, it being understood that during this depression of the case the tooth 17, which normally engages the lower edge of the plunger or striker, elevates said plunger or striker a limited distance until the upper end of the 60 pawl, which projects slightly beyond the tooth 17, engages a cam-face 22 upon the lower end of the tripping member, whereupon the plunger is released and the spring 19 forces the plunger downwardly with considerable force 65 against the upper end of the punch-rod 4, and

thereby produces the desired indentation. The tooth 17 is located some distance above the upper end of the punch-rod 4, and therefore permits the plunger to be moved through such distance by the action of the spring 19 before 70 striking the upper end of the punch-rod. It is thus apparent that two forces are applied to make the indentation, one by the pressure of the operator upon the case or handle and the other by the instantaneous blow produced 75 by the plunger 14 and spring 19.

The central tubular body 1 is provided with an inner annular shoulder 23, which serves to limit the downward movement of the plunger, the shoulder 23 and the shoulder 17 of 80 the pawl 13 being so relatively arranged that when the plunger is seated on the shoulder 23 the shoulder 17 is in position to engage the plunger when the punch-rod is elevated or, more properly, when the handle or case is depressed. 85

Having thus described our invention, we claim as new and desire to secure by Letters Patent—

In a center-punch, comprising a tubular 90 body having a threaded upper end, and a cap screwed on said threaded end, a tip removably secured to the lower end of said body, a spring-pressed punch-rod in said tip, a head on said rod extending into said body, said head being 95 recessed with an upright pawl entering said recess at its lower end, the upper end of the pawl bearing against the interior of the body, a solid plunger of the same cross-section throughout arranged in the body, a spring 100 seating directly upon the upper end of said plunger and bearing against the interior of the cap, said cap being concaved on its under face to form a seat for the spring to retain the latter in position, said plunger having a lengthwise groove formed therein, a trip member arranged in said groove, said trip member formed of an elongated strip of material having its lower end curved inwardly to bear against the bottom wall formed by the plunger-groove, said threaded portion of the body adjacent its lower end being formed with an aperture, a rivet extending through said aperture and secured to the upper end of said trip member, said plunger-groove receiving 110 the upper end of the said pawl when the latter is tripped, said inwardly-curved lower end of the trip member forming a cam-face on its outer face, said pawl having an inwardly-extending shoulder normally engaging the said plunger and retaining the latter in its upright position. 115

In testimony whereof we have signed our names to this specification in the presence of two subscribing witnesses.
